CLAIM

The ornamental design for a handle for nutrient delivery pacifier as shown and described.

DESCRIPTION

FIG. 1 is a perspective view of a handle for nutrient delivery pacifier showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is perspective view thereof, illustrated in use attached to a traditional pacifier; and,

FIG. 9 is an exploded view of the nutrient delivery pacifier shown in FIG. 8.

In the drawings, the equal-length broken lines on the handle for nutrient delivery pacifier depict unclaimed portions thereof. In FIGS. 8-9, the equal-length broken lines showing a traditional pacifier depict unclaimed environmental structure. The dash-dot-dash broken lines define the boundaries of the claim. All broken lines form no part of the claim.

1 Claim, 8 Drawing Sheets
